Primary Examiner — John Windmuller(74) *Attorney, Agent, or Firm* — Knobbe, Martens, Olson & Bear, LLP(57) **CLAIM**

The ornamental design for a wolf clip with serrated top and bottom contact, as shown and described.

DESCRIPTION

FIG. 1 is a front perspective view of the wolf clip with serrated top and bottom contact of the present design;

FIG. 2 is a rear perspective view thereof;

FIG. 3 is a front elevational view thereof;

FIG. 4 is a rear elevational view thereof;

FIG. 5 is a right side elevational view thereof, the left side elevational view being a mirror image thereof;

FIG. 6 is a top plan view thereof; and,

FIG. 7 bottom plan view thereof.

Broken lines are used to illustrate features of the wolf clip with serrated top and bottom contact which form no part of the claimed design.
